DESIGN FOR A VALVE TOOL

Cornelius J. Kennedy, Denver, Colo.

Application July 14, 1936, Serial No. 63,831

Term of patent 3½ years

To all whom it may concern:

Be it known that I, Cornelius J. Kennedy, a citizen of the United States of America, residing at Denver, in the county of Denver and State of Colorado, have invented a new, original, and ornamental Design for a Valve Tool, of which the following is a specification, reference being had to the accompanying drawing, forming part hereof.

In the drawing:

Fig. 1 is a side elevation of a valve tool, illustrating my new design.

Fig. 2 is a bottom view thereof, looking upward.

I claim:

The ornamental design for a valve tool, as shown.

CORNELIUS J. KENNEDY.
